US00D721705S

(12) **United States Design Patent**
Lim et al.

(10) **Patent No.:** **US D721,705 S**
(45) **Date of Patent:** **** Jan. 27, 2015**

(54) **MOBILE COMPUTING DEVICE**

(75) Inventors: **Sunghun Lim**, Bethpage, NY (US);
Robert A. Spano, Smithtown, NY (US);
Carl DeGiovine, Shirley, NY (US)

(73) Assignee: **Symbol Technologies, Inc.**, Holtsville, NY (US)

(**) Term: **14 Years**

(21) Appl. No.: **29/427,761**

(22) Filed: **Jul. 23, 2012**

(51) **LOC (10) Cl.** **14-02**

(52) **U.S. Cl.**

USPC **D14/426**

(58) **Field of Classification Search**

USPC D14/420, 426–430, 453, 341–347, 412, D14/439, 137, 138, 191, 496, 147, 148, 247, D14/248, 144; D13/107, 184; 358/473; 235/462.43, 462.45, 462.47, 462.48, 235/462.44, 462.46, 487, 472.01, 472.02; 16/110.1, 430, 431; 439/133, 135; 709/219, 201, 224, 203; 710/73; 320/114, 115, 123; 361/679–683; 382/313, 321; 455/575.1–575.4, 561, 455/572, 414.1, 550.1, 417, 411, 556.2, 455/564, 566, 41.2, 418, 466, 90.1, 517; D18/2, 7, 11; D21/329, 517; 400/486, 400/472, 489; 341/20, 22, 26; 379/112.01, 379/368, 434, 433.01–433.13; 715/864, 715/780, 816; 248/918

Primary Examiner — Susan Moon Lee

(57) **CLAIM**

The ornamental design for a mobile computing device, as shown and described.

DESCRIPTION

FIG. 1 is a front perspective view of an ornamental design for a mobile computing device;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

Broken lines and entirely unshaded portions contained within broken lines are not claimed.

1 Claim, 6 Drawing Sheets
